UNITED STATES PATENT OFFICE.

HOWARD W. ROBERTS, OF PHILADELPHIA, PENNSYLVANIA.

RUBBER-STAMP-FILING CABINET.

1,249,503.

Specification of Letters Patent. Patented Dec. 11, 1917.

Application filed May 4, 1917. Serial No. 166,280.

To all whom it may concern:

Be it known that I, HOWARD W. ROBERTS, a citizen of the United States, residing at Philadelphia, in the county of Philadelphia 5 and State of Pennsylvania, have invented certain new and useful Improvements in Rubber-Stamp-Filing Cabinets, of which the following is a specification.

My invention consists of improvements in 10 rubber stamp filing cabinets, and is particularly adapted for use in the shipping departments of stores or other business houses. One object is to so construct my invention that by its use a clerk or other 15 person in charge of the department can quickly determine the nature of the credit of any customer as well as the address or other information relative to the customer.

Another object is to make my invention of 20 simple construction and so that the several parts can be easily and quickly manipulated.

These objects, and other advantageous ends which will be described hereinafter, I attain in the following manner, reference 25 being had to the accompanying drawings in which—

Figure 1 illustrates a front elevation of my invention.

Fig. 2 is a top plan view of Fig. 1.

Fig. 3 is a section on the line 3—3 of 30 Fig. 1.

Fig. 4 is a longitudinal section of one of my improved rubber stamps.

Fig. 5 is a perspective view of one of my 35 improved rubber stamps.

Fig. 6 is an enlarged fragmentary plan view taken on the line 6—6 of Fig. 1.

Referring to the drawings, 1 is a supporting frame having a base 2 and two standards 40 3 and 4 which are connected at their tops by a bar 5. Vertically extending ribs 6 and 7 project inwardly from the standards 3 and 4 and rails 8 and 9 which are preferably made of sheet metal, form a facing for 45 said ribs and also form guides for two rubber stamp filing panels 10 and 11 in a manner hereinafter set forth.

The rails 8 and 9 have their front and 50 rear edges turned as shown at 12. These turned edges are arranged at opposite sides of the portion of said rails which form the facing for said ribs 6 and 7, it being noted that each of the rails follows the contour of the cross section of said ribs and extends

partway along the inner face of its respective standard as clearly shown in Fig. 6.

The panels 10 and 11 are designed to slide between the turned ends 12 of the rails in a manner similar to the movable sash of a window. The panel 10 has end flanges 13 60 and 14 which slide between the forward turned ends of the rails 8 and 9.

Ribs 15, 16, and 17, which are formed by bending the panel at different points throughout its width, extend substantially 65 vertical and provide channels 18 and 19. The panel 11 also has forwardly extending ribs 20, 21, and 22 which provide channels 23 and 24 which extend vertically throughout the height thereof.

The panel 11 has rearwardly extending flanges 25 which fit between the rear turned ends 12 of the rails 8 and 9 so as to slide therein. The standards 3 and 4 are provided with weight wells 26 and 27 for sash 70 balancing weights 28 and 29. These weights 28 and 29 have cables or ropes 30 and 31 secured thereto and which pass over anti-friction rollers 32 and 33 which are positioned on the tops of the standards 3 and 4. 80 The ropes 30 and 31 are also connected by hooks 34 or other suitable means to the sides of the ribs 15 and 17 of the panel 10. The standards 2 and 3 are also provided with weight wells 35 and 36 (see Fig. 2) in which 85 slide weights 37.

Ropes 38 and 39 are connected to the weights 37 and pass over anti-friction rollers 40 and 41 which are mounted on the tops of the standards 3 and 4. The ropes 38 and 90 39 are also connected to the panel 11 by means of hooks 42 which engage the sides of the ribs 20 and 22.

The channels 18, 19, 23, and 24 form receptacles for rubber stamps 43. Each of 95 these rubber stamps, as illustrated, consists of an elongated block 44. The rear surface of the block is provided with a facing of rubber 45 which contains raised letters of any of the usual types which form, for example, the name of a customer, his address, credit number, and other information.

The front surface 46 of the block 44 has the name of the customer marked thereon together with the address, credit number or 100 other information which will enable a clerk to quickly locate the desired stamp.

The end 47 of each of the blocks 44 has

a cylindrical hole 48 into which is forced one end of a coiled spring 49. The length of the block 44 is slightly shorter than the width of any of said channels in the panels 5 10 and 11, the spring 49 being compressible so that when the stamps 43 are placed within their respective channels, the spring will exert a thrust longitudinally of the block 44 by its engagement with the side of the 10 adjacent rib, such for example as clearly shown in Figs. 1, 2, and 6.

The stamps 43 may be arranged alphabetically in column formation within the 15 several channels 18, 19, 23, and 24, and when not in use, the panels can be both raised 20 into the position occupied by the panel 11 in Fig. 1. Thus, any number of panels may be employed following out the principle set forth relative to the foregoing description, 25 and when a clerk desires to secure the stamp belonging to a certain customer, he pulls down the panel containing that particular stamp and he can freely remove it by exerting a slight pressure to compress the spring of that particular stamp.

The blocks 44 of the stamps 43 are preferably made wedge-shape on their front portions as shown at 50 so that finger room will be provided to facilitate the removal 30 and insertion of the stamps.

It will be noted that the springs 49 are located adjacent the rear of the blocks 44 so as to permit the friction bearing against the ribs of the panels. When it is desired 35 to insert one of the stamps within a channel, the corner of the block having the spring therein is first inserted and the outer end of the spring 49 is pressed against the side of the rib. The spring is then compressed 40 and at the same time the block 44 can be rocked or swung into the position illustrated in the drawings. As soon as manual pressure is released, the spring will automatically move the opposite end of the 45 block into frictional engagement with the oppositely disposed rib, thereby frictionally holding the block in place.

The several parts of my invention, there-

fore, can be quickly and easily operated and are of substantial constructions. Thus, my 50 invention is of extremely practical use.

While I have described my invention as taking a particular form, it will be understood that the various parts of my invention may be changed without departing 55 from the spirit thereof, and hence I do not limit myself to the precise construction set forth, but consider that I am at liberty to make such changes and alterations as fairly come within the scope of the appended 60 claims.

Having thus described my invention, what I claim as new and desire to secure by Letters Patent is:

1. A filing cabinet comprising a supporting frame, slideable panels having channels formed therein, stamps positioned within said channels, springs interposed between said stamps and the walls of said channels to frictionally hold the stamps within the 70 channels, substantially as described.

2. A filing cabinet comprising a supporting frame, slideable panels having channels formed therein, stamps positioned within said channels, said stamps having holes 75 therein, coiled springs mounted within said holes and having end portions designed to bear against the sides of said channels to frictionally hold the stamps within the channels, substantially as described.

3. A stamp filing cabinet comprising a supporting frame including standards spaced apart, rails on said standards, panels slidably secured to said rails and having forwardly projecting ribs providing channels, stamps within said channels, and means for frictionally holding the stamps within said channels, substantially as described.

In testimony whereof I have signed my 90 name to this specification in the presence of two subscribing witnesses.

HOWARD W. ROBERTS.
